ATTORNEYS

a bolt having a casing adapted to rest on top of a window sash, said bolt comprising a rectangular shaped body, a tongue formed on one side of said bolt extending outwardly from said casing, a recess having an arcuate shaped end formed in said body, recesses in the opposite ends of said body to permit a fastener to pass through said casing to secure said casing to said window sash, a key having a stem, a blade portion on said stem, a shoulder portion on said blade portion adapted to engage the inner sides of said recess and a small portion of the arcuate shaped end of said recess for the movement of said bolt, and said blade portion overlying said bolt to retain said bolt in horizontal relation to said casing and in engagement with the bottom of the casing to guide the movement of said bolt during the operation of said bolt, and lugs positioned at

the opposite rear corners of the casing to receive the bolt as it is withdrawn into the casing.

ETNA J. ALBRITTON.
